UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

COUNTERBALANCING MECHANISM FOR HEADS OF PRESSING MACHINES

Application filed April 12, 1927, Serial No. 183,197. Renewed March 14, 1929.

The invention relates to pressing machines as garment and laundry pressing machines and has for its object a particularly simple and efficient counterbalancing means as 5 springs and mechanism for compensating for the tensioning of the springs during the closing of the press whereby the effective force of the counterbalancing springs on the head is practically the same in all positions of the 10 head.

The invention consists in the novel features and in the combinations and constructions hereinafter set forth and claimed.

In describing this invention reference is 15 had to the accompanying drawings in which like characters represent corresponding parts in all the views.

Figure 1 is a fragmentary elevation of a 20 pressing machine embodying my invention, the position of the parts when the press is opened being shown in dotted line.

Figure 2 is an elevation looking to the right in Figure 1, parts being omitted.

1 designates the buck of a pressing machine, which is suitably supported by a frame 25 a portion of which is shown at 2.

3 is the head movable toward and from the buck and carried at the front end of the lever 4 pivoted at 5 between its ends to the frame 2.

30 The head 4 is operated by any suitable mechanism connected to the rear arm of the lever 4, the mechanism being here shown as a toggle consisting of links 6 and 7 pivoted together at 8, the former being pivoted at 9 to the rear 35 arm of the lever 4, and the latter at 10 to the rear leg of the pressing machine, and at a point near the toggle joint to an arm of a pedal lever or power actuating lever 11. The press here shown is designed to be first closed 40 by pulling down on the head 3 until the toggle consisting of the links 6, 7 is straightened, and then final pressure applied by applying power to the lever 11.

As is well known by those skilled in the art, 45 the head 4 is counterbalanced by weights or springs, or both, and also as the head moves from open position shown in dotted lines, Figure 1, to closed position, the effective length of the lever arm carrying the head 3 increases. That is, the vertical line passing

through the center of gravity of the head 3 moves farther away from the pivot 5 of the lever, as the head closes, and this in effect amounts to the lengthening of the lever arm.

This invention relates to means for compensating the changes in conditions, that is, the increase of the effective length of the yoke arm, and the increase in the tension of the counterbalance springs.

The spring means are here shown as a plurality of springs 12 carried by the frame and acting upon a movable abutment 13, and the motion transmitting means between this abutment 13 and the rear arm of the lever 4 consists of a lever 14, pivoted at 15 to the frame 65 of the pressing machine, and having one arm substantially parallel to the rear arm of the lever 4 and connected thereto by a link 16, and having its other arm 17 arranged to effectively shorten the lever arm as the springs 12 tension during the closing of the press head.

The arm 17 is connected by a link 18 to the abutment 13, and this arm 17 is in its most effective position or where it obtains the longest effective lever arm just as the head 75 starts toward its closed position. At this time the arm 17 makes a right angle with the link 18, and hence the arm 17 is in its most effective position, and the arm 17 moves into a position where it makes an acute angle with the link 18 as the press closes, and as the springs 12 tension, so that the effective leverage of the arm 17 is lessened when the springs are at a greatest tension. The angular position of this arm 17 relatively to the 80 link 18 is such that any differences due to the effective increase in leverage of the head 3 on the arm 4 as the head closes, and the increase in tension of the springs 12 as the head closes, 85 is compensated for in order that the effective counterbalancing force on the lever 4 is substantially constant in all positions of the head 3.

As the rear arm of the lever 4 and the long arm of the lever 14 are parallel and substantially equal in length, the changes of angular position of one compensates for the changes of angular position of the other.

What I claim is:

1. A pressing machine including a frame, 100

a buck, a head movable toward and from the buck, a lever pivoted between its ends to the frame and carrying the head, counterbalancing springs, and motion transmitting means between the springs and the lever comprising a lever element, a link pivoted at one end to an arm of the lever element, connections between the other arm of the lever element and the lever carrying the head, and means connecting the other end of the link to the springs, the arm of the lever element connected to the link being arranged to move into a position at an acute angle to the link as the springs tension during the closing of the press whereby the leverage of the lever element becomes less effective as the springs tension.

2. A pressing machine including a frame, a buck, a head movable toward and from the buck, and a lever pivoted between its ends to the frame, and carrying the head, counterbalancing springs and motion transmitting means between the springs and said lever comprising means for compensating for the tensioning of the springs during the closing of the press head whereby the effective force of the counterbalancing springs on the head is substantially equal in all positions of the head, said compensating means comprising a lever element, a link connected at one end to the lever element, and at its other end to the springs, connections between the other arm of the lever element and the lever carrying the head, the lever element being movable from a position at a right angle to the link into a position at an acute angle to the link as the press head closes and the springs tension.

3. A pressing machine comprising a buck, a head movable toward and from the buck, a lever pivoted to the frame and carrying the head, a second lever pivoted to the frame between its ends, a link connecting one arm of the second lever to the first lever, counterbalancing springs, a spring abutment coacting with the counterbalancing springs and a link connecting the other arm of the second lever and the spring abutment and means for actuating the first mentioned link.

4. In a pressing machine, the combination of cooperating pressing elements, one of which is movable toward and from the other, means for actuating the movable element to close the press, a counter-spring, motion transmitting mechanism connected to the movable element and the spring to open the press and including means for compensating for the tensioning of the spring during the closing of the press whereby the force of the spring tends to remain constant in all positions of the movable element, said means comprising a lever arm and a link connecting the lever arm and the spring, the lever arm being normally arranged at a right angle to the link and the link extending parallel to the

direction of the tensioning movement of the spring and said lever arm being movable during the closing of the press into a position at an acute angle to the link and connections between said lever arm and the movable pressing element.

5. In a pressing machine, the combination of cooperating pressing elements, one of which is movable toward and from the other, means for actuating the movable element to close the press, a counter-spring, motion transmitting mechanism connected to the movable element and the spring to open the press and including means for compensating for the tensioning of the spring during the closing of the press whereby the force of the spring tends to remain constant in all positions of the movable element, said compensating means including a lever with arms operatively connected to the counter spring and the movable element, the arms being disposed so that the leverage on the spring will lessen as the movable element of the press closes.

6. In a pressing machine, the combination of cooperating pressing elements, one of which is movable toward and from the other, means for actuating the movable element to close the press, a counterbalancing spring for opening the press, connections between the spring and the movable element, comprising spaced apart levers having arms extending in general directions parallel to each other, one lever being connected to the movable pressing element, a link connecting said levers and means connecting the other lever and the spring, comprising an additional lever arm and a link connected thereto and to the spring, the additional lever arm being normally arranged at substantially a right angle to the axial line of the spring and to the link connected thereto, and movable into a position at an inclined angle to said link connecting it and the spring as the press closes, the additional lever arm being connected to said other lever to move therewith.

In testimony whereof, I have hereunto signed my name, at Syracuse, in the county of Onondaga, and in the State of New York, this 28th day of March, 1927.

ERNEST DAVIS.
